(57) **CLAIM**

The ornamental design for a fishing sinker, substantially as shown and described.

DESCRIPTION

FIG. 1 is a front elevational view of a fishing sinker showing my novel design, wherein the fishing sinker resembles a firearm ammunition shell casing;

FIG. 2 is an axonometric frontal perspective with $\frac{1}{4}$ a cut removed to highlight interior thereof.

FIG. 3 is a right side elevational view of the sinker described in FIG. 1;

FIG. 4 is a left side elevational view thereof;

FIG. 5 is a top plan view of the sinker described in FIG. 1;

FIG. 6 is a bottom plan view of the sinker described in FIG. 1;

FIG. 7 is an axonometric bottom perspective of the sinker described in FIG. 1;

FIG. 8 is an axonometric bottom perspective with $\frac{1}{4}$ cut removed to highlight interior thereof;

FIG. 9 is an axonometric frontal perspective thereof;

FIG. 10 is an axonometric frontal perspective with $\frac{1}{4}$ cut removed to highlight interior of the sinker described in FIG. 1; and,

FIG. 11 is a front perspective view of the sinker as described in FIG. 1.
